UNITED STATES PATENT OFFICE

100,779

DESIGN FOR A WALL UNIT FOR A STORE INTERIOR

Abraham D. Kaner, University City, Mo.

Application April 1, 1936, Serial No. 61,893

Term of patent 7 years

To all whom it may concern:

Be it known that I, Abraham D. Kaner, a citizen of the Republic of Russia, residing at University City, in the county of St. Louis and State of Missouri, have invented a new, original, and ornamental Design for a Wall Unit for a Store Interior, of which the following is a specification, reference being had to the accompanying drawing, forming part thereof.

Figure 1 is a perspective view of a wall unit for a store interior, showing my new design as seen from the front of the store; and

I claim:

The ornamental design for a wall unit for a store interior, as shown.

ABRAHAM D. KANER.
